US0D1063755S

(12) **United States Design Patent** (10) **Patent No.:** **US D1,063,755 S**
(45) **Date of Patent:** **** Feb. 25, 2025**

(54) **MULTI-ENGAGEMENT SECURING SURFACE**

(71) Applicant: **TailHand Co.**, Centennial, CO (US)

(72) Inventors: **Michael Alvin Ruhs**, Centennial, CO (US); **Suzanne Elaine Ruhs**, Centennial, CO (US); **Daniel Schilk**, Scottsdale, AZ (US); **Chad Daniel Attlesey**, Oronoco, MN (US)

(73) Assignee: **TailHand Co.**, Centennial, CO (US)

(**) Term: **15 Years**

(21) Appl. No.: **29/833,234**

(22) Filed: **Apr. 1, 2022**

(51) LOC (15) Cl. **12-16**

(52) U.S. Cl.

USPC **D12/412**

(58) **Field of Classification Search**

USPC ... D12/196, 221, 406, 412, 413, 414, 414.1; D15/127; D6/406.6, 552; D3/304-306

CPC B60R 9/04; B60R 9/045
